No. 837,994.

PATENTED DEC. 11, 1906.

J. C. WINDER.
MAGNETIC SEPARATOR.
APPLICATION FILED MAY 5, 1906.

UNITED STATES PATENT OFFICE.

JAMES CLARENCE WINDER, OF EAST POINT, GEORGIA, ASSIGNOR TO
E. VAN WINKLE GIN & MACHINE WORKS, OF ATLANTA, GEORGIA.

MAGNETIC SEPARATOR.

No. 837,994.

Specification of Letters Patent.

Patented Dec. 11, 1906.

Application filed May 5, 1906. Serial No. 315,827.

To all whom it may concern:

Be it known that I, JAMES CLARENCE WINDER, a resident of East Point, in the county of Fulton and State of Georgia, have 5 invented certain new and useful Improvements in Magnetic Separators; and I do hereby declare the following to be a full, clear, and exact description of the invention, such as will enable others skilled in the art to 10 to which it appertains to make and use the same.

My invention relates to improvements in magnetic separators for use with cotton-seed delinters, cotton-gins, dust-flues, and in any 15 place where it is desirable to separate magnetic from other substances—such as cotton, cotton-seed, or non-magnetic metals—the object of the invention being to improve and simplify such separators and to increase the 20 efficiency of the same.

A further object is to so construct the separator as to insure the arrest of such objects as may be cylindrical in shape, and therefore liable to roll.

25 A further object is to construct the separator in such manner as to avoid all possibility of fire from overheated electric wires.

With these objects in view the invention consists in certain novel features of construction and combinations and arrangements of parts, as hereinafter set forth, and pointed 30 out in the claims.

In the accompanying drawings, Figure 1 is a perspective view showing an application of 35 my improvements. Fig. 2 is a view showing the side of the separator opposite that which is shown in Fig. 1. Fig. 3 is a longitudinal sectional view. Fig. 4 is a transverse sectional view.

40 1 represents a trough or chute, which may be the feed-hopper of a delinter, cotton-gin, or other machine in the use of which it is desirable to separate magnetic particles or devices from the material being treated, so as to 45 avoid injury to the mechanism, which such particles or devices might otherwise cause.

In the application of my invention shown in the drawings the separator is hinged to the side of the trough or hopper, so that when it 50 is closed it will form a part of the wall of said trough or hopper and be disposed in operative position to arrest magnetic particles which may attempt to pass to the operating parts of the machine.

In constructing my improved separator I 55 employ a strip 2, preferably of wood, having a series of three parallel grooves 3 in one face. In these grooves bars 4 5 6 of iron or steel are secured, preferably by means of screws, the heads of the screws lying flush with the exposed faces of the bars. The wooden strip 2 is provided at intervals with openings 7 for the accommodation of electromagnets, each of which is constructed with three poles secured to the respective bars 4 5 6 by means 60 of countersunk screws. In constructing the magnet I employ three iron or steel plates 8 9 10, to be secured, respectively, to the bars 4 5 6 by means of the countersunk screws above referred to, and these plates are separated from each other by means of thimbles 11 of iron or steel. The several plates and the spacing-thimbles are secured together by means of a transverse bolt. The spaces between the plates 8 9 10 are occupied by 70 helices 12 13, included in series with each other and with a suitable source of electric current. The helices are so wound on the thimbles 11 that the two outer plates will be 75 of one polarity and the intermediate plate 9 of the opposite polarity. In other words, each magnet is made with two salient poles 8 10 and an intermediate consequent pole 9. It will therefore be apparent that the bars 4 and 6 will be of the same polarity (positive, 80 for instance) and the intermediate bar 5 will be of the opposite or negative polarity. It has been found in practice that with such arrangement of magnetized bars the separator is much more efficient than where two bars 85 forming the terminals or pole-pieces of bipolar magnets are employed. With my improved arrangement should a cylindrical object or any device which is liable to roll engage the bars 4 and 5 its progress through the feed-hopper would be promptly checked, and it 90 would be positively arrested on bridging the bars 5 and 6.

Several tripolar magnets, such as above 95 described, may be employed with a single series of bars 4 5 6, according to the length of the separator, the several magnets being secured to the bars at intervals, and the helices of all the magnets will preferably be arranged 100 in series with each other and with the source of current. In order to render the magnets easily removable, the helices of one magnet 105 may be connected with the helices of adja-

cent magnets through binding-posts 13^a, and these binding-posts are located on plates 14 of insulating and fireproof material, and the wires leading from the helices to the binding-posts are passed through tubes 15, set into the face of the wooden strip 2, in order to avoid possibility of the wooden strip 2 becoming ignited from overheated electric conductors.

10. In addition to the advantage above pointed out in the use of my improved magnet I am enabled to produce magnetic bars of great efficiency, and the whole device is made very compact and powerful.

15. Various slight changes might be made in the details of construction of my invention without departing from the spirit thereof or limiting its scope, and hence I do not wish to limit myself to the precise details herein set forth.

Having fully described my invention, what I claim as new, and desire to secure by Letters Patent, is—

1. In a magnetic separator, the combination with a support of non-magnetic material having slots, and three magnetic bars spaced apart and sustained by said support, of a

magnet comprising three plates projecting through the slots in the base and secured respectively to said strips, thimbles separating said plates, helices wound on said thimbles to energize the central plate with one polarity and the end plates with the opposite polarity, and means securing said plates, thimbles and helices together.

2. In a magnetic separator, the combination with a strip or support having a series of slots and a series of three magnetic bars disposed upon said strip or support, of a series of electromagnets projecting through the slots in said strip or support, each of said magnets having three poles secured to the respective bars, insulating-bars secured to said strip or support, binding-posts secured to said strip or support, electric conductors between the binding-posts and the helices of the magnets, and tubes inclosing said electrical conductors.

In testimony whereof I have signed this specification in the presence of two subscribing witnesses.

JAMES CLARENCE WINDER.
